DRILLING MACHINE

Edward G. Lewis, Columbus, Ohio, assignor to
The Jeffrey Manufacturing Company, a corpora-
tion of Ohio

Application August 18, 1932, Serial No. 629,336

52 Claims. (Cl. 255—51)

My invention relates to a track mounted drilling machine particularly adapted for use in coal mines although it may have a general application.

5 An object of the present invention is to provide improved and efficient apparatus for enabling a track mounted drilling machine to drill holes in advance of a mine track at various elevations at the working face either at or near 10 the floor or at or near the roof of the mine chamber or at intermediate points and also at various points extending from the floor to the roof near the ribs or side walls of the entry in which the mine track is laid.

15 Another object of my invention is the provision of improved and efficient controlling and adjusting mechanism to enable the drill to be operated in any one of many different positions at an upright working face.

20 A further object of the invention is the provision of fluid pressure mechanism for feeding a rotary drill and for withdrawing the same from the drill hole.

Another object of the invention is to provide 25 motor-operated mechanism including fluid pressure motors for adjusting and operating the rotary drill and controlling such adjustment and operation by interlocking mechanism to prevent interference between adjustments of the drill 30 and the operations thereof.

A still further object of the invention is to provide drilling apparatus embodying more efficient and economical construction which shall be more convenient in operation than previously 35 known drilling apparatus.

Other objects of the invention will appear hereinafter, the novel features and combinations being set forth in the claims hereto appended.

In the accompanying drawings Fig. 1 is an elevational view of the complete track mounted machine;

Fig. 2 is a plan view of the construction shown in Fig. 1;

Fig. 3 is a plan view of the drilling mechanism mounted on a turntable but detached from the truck, parts in section showing the gearing for driving the main drill shaft;

Fig. 4 is an enlarged vertical sectional view taken on the line 4—4 of Fig. 2 looking in the direction of the arrows;

Fig. 5 is an enlarged vertical sectional view taken on the line 5—5 of Fig. 1 looking in the direction of the arrows;

55 Fig. 6 is a vertical sectional view taken on the

line 6—6 of Fig. 3 looking in the direction of the arrows;

Fig. 7 is a diagrammatic view showing the controlling apparatus for the hydraulic motor; and

Fig. 8 is a diagrammatic view similar to Fig. 7 to show in comparison with the latter the interlocking mechanism to prevent both hydraulic motors from being operated at the same time.

In Figs. 1 and 2 I have shown the drilling apparatus mounted upon a truck generally designated by the reference number 9, this truck being provided with wheels 10 which are adapted to travel on a mine track 11 which may extend along an entry in a coal mine between the ribs or walls adjacent an upright working face in advance of the mine track.

Mounted on the truck 9 is an electric motor 12 the armature of which is connected to a pinion 13 meshing with the gear 14 keyed to a shaft 15 which carries a sprocket connected by a sprocket chain 16 meshing with a larger sprocket keyed to the rear axle 17 of the truck. A suitable controller 18 operated by a handle 19 and comprising resistance in the motor circuit in a well-known manner, may be provided to start, stop, reverse and control the speed of the motor 12 so that the truck propelling mechanism may be operated either at a transport speed or at a drill feeding speed.

Also keyed to the shaft 15 is a sheave wheel 20 which is connected by means of the endless rope 21 to a larger sheave wheel 22 for driving the reel 23 on which the electric cable 24 is wound for the purpose of connecting the electric motors 12 and 25 on the drilling machine to a distant source of electric power supply in accordance with the position of the truck on the mine track in the mine. It should be understood that the motor 12 may be reversed so as to effect propulsion of the truck and drilling apparatus in either direction along the mine track 11, the reel 23 being rotated in the proper direction to wind up or pay out the cable 24 in accordance with the direction of travel of the truck.

The motor 12 is mounted in a frame 26 which is secured to the top of the truck frame 9. Secured to the top of the frame 26 is a semi-circular plate 27 to which is pivotally connected for rotation on an upright axis the turntable 28. The pivotal connection between the plates 27 and 28 is shown in Fig. 4 as comprising a vertical housing 29 in which is mounted a ball-bearing 30 adjusted by a nut 31 threaded on the housing 29 and secured in adjusted position by means of the set screw 32. The central portion of the housing 29 is tubular

and extends loosely through an opening 33 in the turntable plate 28. The nut 31 is provided with a cylindrical extension 34 which fits into the circular hole in the stationary plate 27. A washer 35 surrounds the tube 36 and is located between the top of the nut extension 34 and the bottom edges of the hole 33. The ball-bearing 30 is located in an inverted circular channel in the housing 29.

10 Distributed along the forward peripheral portion of the turntable 28 is a plurality of circumferentially spaced-apart supporting rollers 37, 37 each mounted in a housing 38 as shown in Figs. 3 and 6. The housings 38 are bolted to the turntable 28 as indicated at 39, 39 in Fig. 6. Each roller 37 is provided with a bushing 40 journaled on the bearing pin 41.

Secured to the top of the turntable 28 is a cradle comprising vertical spaced-apart supporting plates 42, 42 one of which is shown in elevation in Fig. 1. The drilling unit 43 is pivoted at 44 to the upper forward ends of the cradle plates 42 as shown in Figs. 1 and 4.

The drilling unit 43 comprises an electric motor 25 to the frame 45 of which is provided with spaced-apart bosses 46, 46 as shown in Fig. 3. A rod 47 extends through holes in the bosses 46 and through holes in the upper forward ends of the plates 42. Lock nuts 48, 48 on the outer ends 30 of the rod 47 outside of the plates 42 hold the rod 47 in proper position to serve as journal bearings for the bosses 46 which fit between the inner sides of the plates 42. It will thus be seen that the drilling unit 43 is pivoted to the turntable for up 35 and down tilting movements relatively thereto on a horizontal axis in the various positions to which the turntable is rotated on the vertical axis of the pivotal connection at 36 between the turntable 28 and the stationary frame 27 40 which is secured to the truck frame 9.

At the rear end of the drill unit 43 on a platform 48 which is secured rigidly to the motor frame 45, is mounted a hydraulic pump 50 to which is connected a flexible hose 51. The hydraulic pump 50 is operatively connected to the electric motor 25 by means of the pinion 52 on the armature shaft and the gear 53 on the hydraulic pump shaft.

The forward end of the armature shaft of the electric motor 25 is provided with a pinion 54 which meshes with the gear 55 keyed to a counter-shaft 56 to which is also keyed a pinion 57 meshing with a gear 58. The reduction gearing comprising the gears 54, 55, 57 and 58 is mounted in a housing 59 secured rigidly to the frame 45. The motor 25 and the reduction gearing are entirely enclosed.

I prefer to pivot the drilling unit 43 on the upper side thereof as indicated at 44 in Fig. 1, so as to reduce the overall height of the machine and enable the latter to operate in relatively low roof mine chambers. As shown in Fig. 4, the pump and the rear portion of the motor 25 are located at the rear end of the support 45, 63 for the motor 25 and the boom 61. The placing of the motor 25 and the pump 50 at the rear end of the drilling unit 43 assists in counterbalancing the latter on a transverse axis 47 and consequently the power necessary for operating the hydraulic motor 130 is reduced. Furthermore, by counterbalancing the drilling unit it may more easily be held in adjusted position when the piston 139 is locked in the cylinder 131.

As shown in Fig. 4 the gear 58 is keyed to a driving shaft 60 which extends longitudinally

through the center of the elongated tubular boom or supporting arm 61.

Bolted at 62, 62 to the housing 45 is a tubular frame 63 the outer end of which is provided with a gear housing 64. A tubular bushing 65 lines the inner wall of the frame 63 and is provided with an annular flange 66 in the housing 64. The rear end of the tubular boom or arm 61 is journaled in the bushing 65.

A sleeve 67 fits into a counterbore against the annular shoulder 68. The rear end of the sleeve 67 has keyed thereto a bushing 69 in which is journalled the rear end of the driving shaft 60.

A worm gear 70 is secured by means of keys 71 to the sleeve 67 and the tubular boom or arm 61 so as to rotate with the sleeve and boom. A washer 72 is located between the rear face of the worm gear 70 and the front face of the annular flange 66. It should be understood that the worm gear 70 is keyed to both the sleeve 67 and the tubular boom or arm 61 so that whenever the worm gear 70 rotates both the sleeve 67 and the boom 61 will rotate with the same. A worm 73 in the lower portion of the housing 64 meshes with the worm gear 70. The shaft 74 for the worm 73 extends to a position outside of the housing 64 and has connected thereto a crank 75 by means of which the worm 73 and the worm gear 70 may be rotated which in turn will effect the rotation of the sleeve 67 and the tubular boom 61 on the axis 20 of the shaft 60 and relatively thereto.

As shown in Fig. 5 a bearing block 76 is inserted into the outer end of the tubular boom 61 and secured thereto to serve to support the bearings 77 and 78 for the shaft 79. To the outer end 35 of the shaft 79 is keyed a bevel pinion 80 which meshes with a double bevel gear 81 having an upper bevel gear face 82 and a lower bevel gear face 83. The double bevel gear 81 is keyed to the upper end of the shaft 84 which is journalled 40 in the bearing 85 in the housing 86, the latter being secured to an extension 87 from the bearing block 76 so as to be rigid therewith.

A housing 88 is pivoted to the housing 86 by a circular tongue and groove connection at 89. 45 This tongue and groove connection serves to interlock the housings 86 and 88 while permitting, relative rotation thereof on the axis of the shaft 84. The bevel gears 80 and 81 may be secured to their respective shafts 79 and 84 by means of the 50 nuts 90 and 91.

At the left-hand end of the housing 88 as viewed in Fig. 5 is a fluid pressure feed cylinder 92 which is held in place on the housing 88 by means of a split ring key 93 seated in an annular recess 55 in the outer surface of the cylinder 92 and engaged circumferentially by the nut 94 which is screw-threaded on the housing 88 at 95. The nut 94 is loose on the cylinder 92 but is provided with an interior shoulder 96 against which the ring key 93 abuts to prevent withdrawal of the cylinder 92 from the housing 88. Movement of the cylinder 92 in the opposite direction is prevented by the key 93 striking against the left-hand end of the threaded tubular portion 97 at 65 the left-hand end of the housing 88 as viewed in Fig. 5.

Splined on the drill shaft 98 by means of a key 99 having a length approximately equal to the length of the cylinder 92, is a bevel gear 100 70 mounted in the bearing 101 at the right-hand end of the housing 88 as viewed in Fig. 5. The bevel gear 100 meshes with the bevel gear 82.

On the left-hand end of the shaft 79 is keyed a clutch member 102 which is adapted to be en- 75

gaged by the movable clutch element 103 which is splined to the driving shaft 60 to rotate therewith but having limited longitudinal movement relatively thereto. By means of eccentric mechanism 104 connected to the movable clutch element 103 the latter may be moved into or out of engagement with the clutch element 102. The eccentric mechanism 104 comprises a circular member extending through a circular opening in the wall of the tube 61 and a cylindrical cup 105 fits in a bracket 106 which is secured to the outer wall of the tube 61. An operating lever 107 is connected by means of a spring 108 to the cup 105 so that the lever 107 may be partially withdrawn to enable the latter to fit into transverse notches in the bracket 106 to hold the clutch 102, 103 either applied or released.

As shown in Figs. 1 and 2 a drill socket and holder 109 is secured to the outer end of the feed shaft 98 and the shank or tail piece of the drill 110 is inserted into the holder 109 to be held thereby for rotation therewith both when the drill is feeding forward axially to drill a hole in the upright coal face and when it is being withdrawn from the drill hole.

As shown in Fig. 4 a supporting platform 111 may be bolted at 112 to an angle-iron 113 which is secured to the turntable 28. Mounted on the platform 111 is an enclosed casing 114 for the usual and well-known starting, stopping, reversing and controller mechanism operated by the crank 115. The mechanism within the casing 114 for controlling the starting, stopping, reversing and speed of the motor 25 is connected by means of the electric cable 116 to the motor 25 as shown in Fig. 4, there being sufficient slack in the cable to permit free movement of the drill unit 48 on its pivot 44 through a wide angle so as to enable the positioning of the drill 110 at the floor and at the roof in mine chambers of various heights.

When the clutch 102, 103 is thrown in by means of the lever 107 and the eccentric mechanism 104 and the clutch elements held in coupled relation, the motor 25 will be operatively connected to the drill 110 to rotate the same. The transmission of power from the motor 25 to the drill to rotate the latter will be through the reduction gearing 54, 55, 57 and 58 shown in sectional plan view in Fig. 3, thence through the shaft 60, the clutch 102, 103, the shaft 79, the bevel gearing 80, 83, 82 and 100, to the shaft 98 and the drill socket 109.

Mounted on the rear end of the feed shaft 98 is the piston 117 fitting in the feed cylinder 92. This piston comprises a sleeve 118 which is screw-threaded on the left-hand end of the bearing block 119.

The bearing block 119 is provided with an annular collar or flange 120 the left-hand face of which as viewed in Fig. 5 serves as a locking abutment for the right-hand end of the screw-threaded sleeve 118. The right-hand face of the flange 120 is adapted to engage the left-hand end of the cup 121 which holds in place a buffer spring 122 which rests against an annular shoulder in the housing 88. An outer annular flange 123 on the cup 121 has a limited movement between spaced-apart annular shoulders in the housing 88. When the feed shaft 98 is in its extreme right-hand position as shown in Fig. 5 the annular flange 120 engages the cup 121 to compress the buffer spring 122. When the feed shaft 98 is retracted or moved to the left as viewed in Fig. 5 the spring buffer will be restored

to its initial position by the spring 122 moving the cup 121 against its left-hand annular shoulder in the housing 88 as viewed in Fig. 5.

Entirely enclosed within the sleeve 118 and held in place by the latter and the bearing block 119 is a ball-bearing 124 secured to the left-hand end of the feed shaft 98 by means of the nut 125. A spacing sleeve 126 on the feed shaft 98 in the housing 88 serves to hold the bevel gear 100 in its bearing 101. During feed of the drill into the coal face while such drill is rotating in the proper direction, hydraulic pressure exerted on the left-hand end of the piston 117 as viewed in Fig. 5, is transmitted to the feed shaft 98 through the ball-bearing 124. At the outer limit of travel of the feed shaft 98 the buffer spring 122 cushions the stopping of the drill and the annular flange 120 acts on the cup 121 to seat the latter to limit the travel of the feed shaft 98. When the drill is retracted by hydraulic suction on the piston 117 the pull on the feed shaft 98 is also exerted through the ball-bearing 124 and consequently no appreciable thrust is exerted on the spacing sleeve 126. The left-hand end of the cylinder 92 as viewed in Fig. 5 is closed by a screw-threaded cylinder head 127 which is provided with a removable screw-threaded plug 128 for a filling opening. During operation the screw-threaded plug is closed and hydraulic pressure exerted through a flexible hose 129.

An elevating hydraulic motor 130 is mounted as shown in Fig. 4 for the purpose of varying the elevation of the drilling unit 48 on its pivot 44. The cylinder 131 of the hydraulic motor 130 is pivoted at 132 to a depending bracket plate 133 secured to the bottom of the housing 63. The piston rod 134 of the hydraulic motor 130 is pivoted at 135 to the standard 136 which is mounted on top of the turntable plate 28. A flexible hose 137 is connected to one end of the cylinder 131 and a flexible hose 138 is connected to the other end of the cylinder 131 so that hydraulic pressure may be exerted on either side of the piston 139 while the hydraulic pressure on the other side thereof is being withdrawn.

The hydraulic system of control which I prefer to use to prevent interference between the operation of the fluid pressure feed motor and the fluid pressure elevating motor is shown in Figs. 7 and 8. The tank 140 for the supply of fluid pressure medium is shown diagrammatically in Figs. 7 and 8. Such tank may be mounted on a platform 141 as shown in Fig. 3 and provided with a screw plug 142 for a filling opening in the top of the tank. A flexible hose supply pipe 143 extends from the side of the tank and is connected to the valves which are mounted on the support 144 shown in plan in Fig. 2.

The valves mounted on the support 144 are diagrammatically illustrated in Figs. 7 and 8 and comprise a check valve 145 and the manually operated valves 146, 147 and 148. Fig. 7 shows the positions of the valves 146, 147 and 148 when the hydraulic motor 130 is to be operated to elevate the drill. Each of the valves 147 and 148 is provided with three separate passageways and are so arranged that the valves will be interlocking in that when the hydraulic motor 130 is being operated the hydraulic feed motor has the supply pressure thereto cut off.

Assuming the piston 117 to be in its left-hand position as shown in Fig. 7 and the handles 149 and 150 of the valves 147 and 148 occupying their full line positions the hydraulic pump 50 when operated in the proper direction by the motor 25

will produce a flow through the pipe 151 in the direction of the arrows 152 through the passageway 153 in the valve 148 to the pipe 157 and thence into the cylinder 131. The flow from the cylinder 131 will be through the pipe 158 into the passageway 154 of the valve 148 and thence through the pipe 155, and through the passageway 156 into the pipe 157. The latter communicates with the pipe 158 which is connected to the intake side of the hydraulic pump 50. If the hydraulic pump 50 continues to operate after the piston 139 reaches the limit of its stroke the check valve 159 in the by-pass pipe 160 will be opened in the direction of the arrow 161 to protect the hydraulic pump 50.

On account of the displacement of the piston rod 134 on the right-hand side of the piston 139 as viewed in Fig. 7 more oil will flow through the pipe 157 into the cylinder 131 than flows out of the same into the pipe 158 for a given movement of the piston 139. The operating handle 162 of the compensating valve 146 being in a horizontal position as shown in Fig. 7 the valve 148 will be open. Consequently the operation of the pump 50 during movement of the piston 139 toward the right as viewed in Fig. 7 will draw from the tank 140 through the pipes 143 and 163 a sufficient amount of oil to enable the pump 50 to operate to supply enough oil to keep the left-hand side of the piston 139 completely filled with oil. It will thus be seen that when the pump 50 operates, the supply of the oil for the cylinder 131 at the left of the piston 139 is drawn partly from the tank 140 and partly from the right-hand side of the piston 139.

When the piston 139 is to be moved from its dotted line position to its full line position the lever 150 is moved to its dotted line position to change the passageways 153 and 154 of the valve 148 to their dotted line positions. When this adjustment is made the valve 147 is left in its full line position shown in Fig. 7. Then upon operating the pump 50 the flow will be in the direction indicated by the arrows 152 through the passageway 153 into the pipe 158 and thence into the cylinder 131 to the right of the piston 139. The flow from the left-hand side of the piston 139 will be through the pipe 157, the passageway 154, the pipe 155, the passageway 156, into the pipe 158, to the intake side of the pump 50. More oil will now flow from the left-hand side of the piston 139 than is pumped into the cylinder 131 at the right-hand side of the piston 139, by reason of the displacement of the piston rod 134. The excess oil will flow through the valve 146, the pipe 163, and the pipe 143, back to the supply tank 140.

It should be particularly understood that when the valve 147 is in its full line position shown in Fig. 7 the piston 117 will be locked against movement in either direction in its cylinder 92. Therefore while the drill unit 43 is being tilted up or down on the pivot 44 the drill cannot be moved outwardly or retracted. In like manner when the valve 148 is in its closed position shown in Fig. 8 the piston 139 will be locked against movement in either direction and the drill unit will be held rigidly at adjusted elevation and inclination relative to the turntable 28 during operation of the drill including feed thereof and withdrawal of the drill from the drill hole.

As shown in Fig. 8 the valve 148 is provided with a central passageway 164 which should be moved to the position shown in Fig. 8 before the feed motor is operated. When the elevating mo-

tor 138 is locked by moving the valve 148 to its position shown in Fig. 8 and it is desired to operate the feed motor the lever 148 may be moved to its full line position whereupon the passageway 165 will connect the pipe 155 to the pipe 129 which leads to the feed cylinder 92. Upon operation of the pump 50 the oil will flow in the direction of the arrows 152 into the cylinder 92 to move the piston 117 slowly toward the right as viewed in Fig. 8 to effect feed of the drill while the same is being rotated by the motor 28 and the power transmission mechanism between this motor and the drill socket 109. If the drill meets with an obstruction or when the piston 117 reaches the right-hand limit of its stroke, continued pressure will be relieved by the flow of oil from the pipe 129 into the pipe 166 and through the check valve 145 which opens in the direction of the arrow 167 at a pre-determined excess pressure. That is to say, when the pressure in the cylinder 92 exceeds a pre-determined amount oil will flow from the pipe 166 through the check valve 146 into the pipe 158 and thence through the pipe 143 back to the supply tank 140.

While the piston 117 is moving in feeding direction the suction connection between the supply tank 140 and the pump 50 will be through the pipes 143, 169, the passageway 170, and pipes 171, 168. It should be noted that the compensating valve 146 is shown closed in Fig. 8 while the feed motor is being operated in either feeding or reTRACTING direction.

When the drill is to be withdrawn from the drill hole the handle 149 is moved to its dotted line position as shown in Fig. 8. Operation of the pump 50 will then cause the oil to flow from the pump through the passageway 165 directly to the supply tank 140. The suction side of the pump, however, will be connected through the pipes 158, 171, the passageway 170 and pipe 129 to the cylinder 92, to the left of the piston 117. The retraction of the drill is therefore dependent upon hydraulic suction exerted in that portion of the cylinder 92 to the left of the piston 117.

The flexibility of the track mounted drill machine due to the various adjustments that can be made is such that when the shaft 84 is horizontal as shown in Fig. 2 the drill may be adjusted to occupy perpendicular positions relative to the coal face either at the floor or at the roof or at any intermediate point. Or the drill may be inclined either upwardly or downwardly on the axis 84 as well as on the pivot 44. The drill unit 43 may be swung horizontally on the vertical axis 36 shown in Fig. 4 and held in adjusted angular position by the pins 172 inserted through holes 173 in the turntable which register with holes 174 in the horizontal supporting plate 27 on top of the motor frame 28. However, when the axis 84 is horizontal and the boom 61 is in an angular position when viewed in plan the drill 110 must be in a radial position relative to the vertical turntable axis. However, drill holes may be made in horizontal planes in fan-shaped relation at various elevations.

When the axis 84 is vertical the drill may be adjusted to drill holes in fan-shaped relation in various intersecting planes such fan-shaped relation being relative either to the upright axis 84 or relative to the upright axis of the turntable.

The supporting arm or boom 61 being tubular may be made of sufficient length to enable the drill to reach the sides of a working face in a wide room the walls or ribs of which extend a relatively long distance from the longitudinal 75

center line of the mine track. A reinforcing tube 175 may be connected to the outer end of the housing 64 as shown in Fig. 4 to lend additional support to the tubular boom 61 and the drilling 5 mechanism mounted thereon.

It should be particularly noted that drilling operations may be carried on at the upright face in advance of the mine track so as to obtain drill holes at right angles to the working 10 face and at any point between the floor and the roof and between the ribs or side walls of the entry. When the boom 61 is swung laterally on the upright turntable axis 36 it may be swung upwardly or downwardly on the pivot 44 so as to 15 position the drill holder 109 either at the floor or at the roof. Then upon turning the crank 75 (Fig. 2) the shaft 74 (Figs. 2 and 4) may be rotated to operate the worm gearing 73, 70 shown in Fig. 4. This will effect turning of the tubular 20 boom 61 so as to shift the axis 84 until it is in a vertical plane parallel to the working face. After this adjustment is made the housing 88 together with the drill may be turned on the axis 84 until the drill is perpendicular to the working 25 face. When the boom 61 is in an angular position inclined laterally and downwardly the axis 84 when in an upright position and when in a horizontal position intersects the vertical plane of the coal face. There are two intermediate positions, however, where the axis 84 is in a vertical 30 plane parallel to the vertical plane of the working face. These two positions are determined by the intersection of a plane in the circle described by rotation of the shaft 84 and housing 35 81 about the axis of the tube 61 and a vertical plane through the intersection between the axis of the tube 61 and the axis of the shaft 84. The shaft 84 may be brought into this line of intersection in two positions so that the drill will be 40 located either on the upper side or the lower side of the tube 61. When the axis 84 is in the line of intersection it will be in a vertical plane and therefore the drill may be adjusted to a position at right angles to the coal face. It will 45 thus be seen that irrespective of the angular position of the boom or irrespective of its lateral position and up or down inclination, the drill may be positioned to drill holes at right angles to the coal face at any point thereof within the 50 reach of the machine.

When the drilling unit 43 is turned to adjusted position on the vertical axis of the turntable, it may be locked in such lateral position. When the drilling unit is inclined upwardly or downwardly on its axis 44 relatively to the turntable, it may be locked in adjusted position by locking the piston 138 in the cylinder 131. Now with the boom 61 in a laterally extending position and in an inclined position it may be desirable 55 to drill a hole in the coal face which extends across the space in advance of the mine track, so that such hole will be parallel to the adjacent rib and parallel to the mine track. The hydraulic motor 92 for feeding the drill axially is 60 adjustable on rectangularly related axes one of which is the axis of the shaft 84 shown in Fig. 5, and the other of which is the axis of the shaft 79 which is the boom axis. By extending a vertical plane parallel to the working face through 65 the intersection between the axes 84 and 79 when the boom extends laterally and is in an inclined position, the correct position of the axis 84 may be ascertained for locating the drill at right angles to the working face. That is to 70 say, by rotating the boom 61 until the shaft 84

is at the intersection between such vertical plane and a plane extending through the shaft 84 at right angles to the shaft 79, the axis 84 will be parallel to the working face. In other words, when the boom 61 is in a lateral and inclined 5 position it should be rotated until the shaft 84 is in a vertical plane parallel to the working face which extends across the space in advance of the mine track. Then the drill may be rotated on the axis 84 until it is at right angles to the 10 working face.

It is preferred to have the boom 61 of such length that the tool holder 109 will be at such distance from the turntable axis 36 that the side walls may be spaced from the center of the 15 mine track more than three times the width of the track gauge. For instance, if the length of the stroke of the piston 117 of the hydraulic feed motor is approximately equal to twice the width of the track gauge and the boom is swung 20 to a position at right angles to the mine track, holes may be drilled in ribs which are located a distance from the turntable axis 36 equal to approximately five times the width of the track gauge. However, the principal advantage in 25 having the boom elongated so that the tool holder 109 will be located at a distance from the turntable axis 36 at least equal to three times the width of the track gauge, is to enable 30 the single boom to support the drill for operation at either side of a wide coal face and in positions at right angles to the coal face at any elevation desired and parallel to and adjacent to the ribs or side walls of the entry. It is desirable in many instances to produce the drill 35 holes at right angles to the coal face and adjacent to the ribs so that when the coal is blasted down the walls of the entry will be in slined continuation. Vertical drill holes may also be produced at any point over a wide area of the 40 roof or floor.

While the drill is operated to produce holes in the ribs or in the roof or floor and while the drill is operated in the coal face in a slanting position relative to the upright plane of the 45 coal face, the truck is held stationary on the mine track either by means of the brake mechanism 188 or by means of sprags blocking the wheels 10 or by means of roof jacks anchoring the truck frame. But when the drill is ad- 50 justed to drill at right angles to the coal face it will be parallel to the mine track and then the drill may be fed by slow traction of the truck either by controlling the motor 12 or by means of reduction gearing of well known construction. For instance, if the coal is relatively soft faster drilling may be obtained by traction feed of the whole machine along the mine 55 track. When the truck is held stationary on the mine track and the hydraulic motor 92 is used to feed the drill the rate of feed will be automatically regulated when unusually hard material is encountered. When the pressure back of the piston 117 builds up to exceed a pre-determined maximum the relief valve 145 shown 60 in Fig. 8 will be automatically opened but the drill will continue to rotate until such hard material has been drilled whereupon the rate of feed will again increase until the drill hole has been completed. The arrangement including 65 the hydraulic feed motor is therefore such as to secure varying rates of feed automatically according to the resistance encountered by the drill. Retraction of the drill may be obtained 70 by one continuous rectilinear return movement 75

of the piston 117 while the drill is being rotated in cutting direction to cause its spiral guide blades to clean the cuttings out of the drill hole.

Inasmuch as the strokes of the piston 117 of 5 the hydraulic feed motor tend to displace the air in the housing 88 openings are provided at 177 and 178 in the bearing block 76 and at 179 in the bearing block 180, and an opening is also placed at 181 in the sleeve 67 shown in Fig. 4. 10 A bleed opening 182 in the housing 45 permits ingress and egress of air in the tube 61 when the piston 117 is moved in the cylinder 92. It should be noted that the bleed opening 182 is 15 distant from the working face. Therefore all parts of the feed motor and all parts of the power transmission mechanism between the housing 45 and the drill remain entirely enclosed. By placing the opening 182 distant from the drill the amount of coal dust that can find 20 its way into the interior of the drilling unit 43 is reduced to a minimum.

It should also be noted that the controllers 18, 114 and the motors 12, 25 are enclosed in flame-proof casings.

25 Obviously those skilled in the art may make various changes in the details and arrangement of parts without departing from the spirit and scope of the invention as defined by the claims hereto appended, and I wish therefore not to be 30 restricted to the precise construction herein disclosed.

Having thus described and shown an embodiment of my invention, what I desire to 35 secure by Letters Patent of the United States is:

35 1. In drilling apparatus, the combination with a hollow supporting arm, of a drill, mechanism for rotating said drill, a housing co-acting with said arm to enclose said rotating mechanism, a fluid pressure feed motor comprising a piston 40 the movement of which tends to displace the air in said housing and said hollow support, and means affording ingress and egress of air into said hollow support at a point distant from the working face where the drill operates.

45 2. Drilling apparatus comprising a fluid pressure motor having a cylinder, a frame for supporting said cylinder, a split ring fitting into an annular groove in said cylinder, and a nut screw-threaded to said frame and having interior annular shoulders for detachably locking said cylinder to said frame.

50 3. In drilling apparatus, the combination with a supporting frame, of a drilling tool mounted thereon, motor-operated mechanism for rotating said drilling tool, a fluid pressure motor for feeding and retracting said drilling tool, and means for controlling said fluid pressure motor to effect feeding of the drilling tool by fluid 55 pressure and the retraction thereof by suction.

60 4. Drilling apparatus comprising an elongated tubular boom, a drive shaft in said boom, a driven shaft in said boom, a clutch between the ends of said shafts and enclosed by the boom, 65 and eccentric mechanism operable from without the boom for connecting and disconnecting said clutch.

65 5. In drilling apparatus, the combination with a portable support, of a drilling tool, mechanism 70 for rotating said drilling tool, a hydraulic motor for feeding and withdrawing said drilling tool, and means for controlling said motor to operate by hydraulic pressure during feeding of said drilling tool and by suction during the withdrawal thereof.

6. In drilling apparatus, the combination with a truck adapted to travel on a mine track, of a drilling tool adjustably mounted thereon, motor operated mechanism for rotating said tool, and a hydraulic motor operating by pressure to 5 feed said tool and by suction to withdraw the same.

7. In drilling apparatus, the combination with a portable support, of an elongated supporting arm pivotally mounted on said support for 10 swinging movement about a horizontal axis, a drilling tool adjustably mounted on the outer end of said elongated supporting arm, a motor carried by said elongated supporting arm to move bodily therewith, a fluid-pressure pump connected to said motor and mounted on said elongated supporting arm to move bodily therewith, mechanism operated by said motor for rotating said drilling tool, means connected between said pump and said drilling tool to feed the same axially, and mechanism comprising a fluid-pressure motor for swinging said arm upwardly and downwardly about its pivot to position said drilling tool. 15 20

8. In drilling apparatus, the combination with a self-propelled support, of a turntable mounted on said support for rotation relatively thereto about a vertical axis, an elongated supporting arm pivotally mounted on said turntable for swinging movement about a horizontal axis, a 30 drilling tool carried at the outer end of said arm, self-contained power-operated mechanism comprising a fluid-pressure pump mounted on said arm to move bodily therewith for operating said drilling tool including rotation and feed thereof, and separate mechanism comprising a fluid-pressure motor for swinging said arm together with said drilling tool on said horizontal axis. 35

9. In drilling apparatus, the combination with a self-propelled support, of a turntable mounted 40 on said support for rotation relatively thereto about a vertical axis, an elongated supporting arm pivotally mounted on said turntable for swinging movement about a horizontal axis, a 45 drilling tool carried at the outer end of said arm, self-contained power-operated mechanism comprising a fluid-pressure pump mounted on said arm to move bodily therewith for operating said drilling tool including rotation and feed thereof, and separate mechanism connected to said 50 pump and comprising a fluid-pressure motor for swinging said arm together with said drilling tool on said horizontal axis.

10. In drilling apparatus, the combination with a portable support, of a turntable thereon 55 rotatable about a vertical axis, an elongated boom pivotally mounted on said turntable for adjustment relatively thereto on a horizontal axis, a drilling tool pivotally mounted on the outer end of said arm, mechanism comprising a fluid-pressure motor for adjusting said arm about said horizontal axis, and self-contained power-operated mechanism comprising a motor and a pump mounted on said arm to move bodily therewith for operating said drilling tool including rotation and feed thereof. 60 65

11. A self-contained drilling unit comprising an elongated support, a motor carried by said support, a pump operatively connected to said 70 motor, a drilling tool mounted on said support, mechanism operated by said motor for rotating said drilling tool, and a fluid-pressure motor operatively connected between said pump and said drilling tool to feed the latter axially while 75

said pump is being driven by said first-named motor.

12. Drilling apparatus comprising a fluid-pressure motor having a piston, a rotary feed shaft, a bearing block, a rotarily screw-threaded connecting flange between said piston and said bearing block, and an abutment collar on said bearing block for clamping engagement by said flange, said piston and said flange and said collar all being of equal diameter.

13. In drilling apparatus, the combination with supporting framework, of a drilling tool mounted thereon, motor operated mechanism for rotating said drilling tool, a fluid-pressure motor for feeding said drilling tool, mechanism comprising another fluid-pressure motor for adjusting the position of said drilling tool, a fluid-pressure pump, and valves arranged in series and connecting said pump to said fluid-pressure motors for controlling the latter to prevent operation of one when the other is operating.

14. In drilling apparatus, the combination with supporting framework, of a drilling tool mounted thereon, means for rotating said drilling tool, a fluid-pressure motor for feeding said drilling tool, another fluid-pressure motor for adjusting the position of said drilling tool, two valves one for each of said fluid-pressure motors, and conduits for connecting a source of fluid-pressure through said valves in series to said fluid-pressure motors so that when one is operating the other may be cut off from such source of fluid pressure.

15. In drilling apparatus, the combination with supporting framework, of a drilling tool mounted thereon, means comprising a fluid-pressure motor for operating said drill, another fluid-pressure motor for adjusting the position of said drill, valves connected in series for controlling said fluid-pressure motors, and conduits connecting a source of fluid-pressure to said fluid-pressure motors so that when either fluid-pressure motor is operating the other may be cut off from such source of fluid-pressure.

45 16. In drilling apparatus, the combination with a support, of a drilling tool mounted thereon, means comprising a fluid-pressure motor for operating said drilling tool, another fluid-pressure motor for adjusting the position of said drilling tool, two valves connected in series for controlling said fluid-pressure motors, and conduits connecting a source of fluid-pressure to said fluid-pressure motors through said valves to enable one motor to be rendered inoperative while the other is operating and to lock the second-named fluid-pressure motor in adjusted position while the other fluid-pressure motor is connected to such source of fluid-pressure.

60 17. In drilling apparatus, the combination with a portable support, of an elongated boom pivoted thereto, a drilling tool mounted on said boom, means comprising a fluid-pressure motor for operating said drilling tool, means comprising another fluid-pressure motor for swinging said boom on its pivotal connection to said portable support, and valves connected in series between a source of fluid-pressure and said motors and operable to effect the operation of only one motor at a time, the other motor being then inoperative by being 65 cut off from such source of fluid-pressure.

70 18. In drilling apparatus, the combination with a portable support, of an elongated boom pivoted thereto, a drilling tool mounted on said boom, mechanism mounted on said boom for operating said drilling tool, said operating mechanism com-

prising a fluid-pressure motor, means comprising another fluid-pressure motor for swinging said boom on said pivotal connection to said pivotal support to adjust the position of said drilling tool, two controlling valves one for each of said fluid-pressure motors, and conduits for connecting said valves in series with each other and a source of fluid-pressure to said fluid-pressure motors, said valves being operable to positions to co-act with said conduits to compel either motor 10 to be cut off from such source of fluid-pressure supply when the other is connected thereto.

19. In drilling apparatus, the combination with a portable support, of drilling apparatus mounted thereon and comprising two separate fluid-pressure motors for operating and adjusting the same, two three-way valves one for each of said motors, and conduits for connecting said valves in series with each other and a source of fluid-pressure through said valves to said motors to enable the 20 fluid-pressure medium to pass through both valves when either motor is operated while the other is cut off from such source of fluid-pressure.

20. In drilling apparatus, the combination with a support, of a drilling tool mounted thereon, 25 means comprising a fluid-pressure motor for operating said drilling tool, another fluid-pressure motor for adjusting the position of said drilling tool, two three-way valves one for each motor, and piping connection between a source of fluid-pressure and said motors through said valves, two passageways in each valve serving for supply 30 and exhaust to and from the corresponding motor and the third passageway in each valve serving to complete the flow line thereby enabling the 35 source of fluid-pressure being cut off from one motor while the other is operating.

21. In drilling apparatus, the combination with a support, of a drilling tool mounted thereon, means comprising a fluid-pressure motor for operating said drilling tool, another fluid-pressure motor for adjusting the position of said drilling tool, two three-way valves one for each of said motors, and piping connections between a source 40 of fluid-pressure and said motors through said valves, said valves being capable of co-acting with said piping connections to prevent both motors 45 from being operated at the same time, one motor being cut off from such source of fluid-pressure when the other is operating.

50 22. Drilling apparatus comprising an elongated boom, a drive shaft in said boom, a driven shaft in said boom, a clutch between the ends of said shafts and enclosed by said boom, and mechanism operable from without said boom for connecting and disconnecting said clutch.

55 23. Drilling apparatus comprising a hollow support, a drive shaft in said hollow support, a driven shaft in said hollow support, a clutch between the adjacent ends of said shafts, and mechanism operable from without said support for connecting and disconnecting said clutch.

60 24. Drilling apparatus comprising a drive shaft, a driven shaft, a clutch between the ends of said shafts, a supporting enclosure for said shafts and 65 said clutch, and mechanism having an air-tight fit in an opening in said enclosure for operating said clutch from without said enclosure.

70 25. In drilling apparatus, the combination with a portable support, of a drilling tool, mechanism for rotating said drilling tool, a fluid-pressure motor for feeding and withdrawing said drilling tool, a controlling valve for said motor, and means comprising conduits connected to said valve and motor for effecting feed of said drill- 75

ing tool by fluid-pressure in said motor when said valve is in one position and withdrawal of said drilling tool by suction in said motor when said valve is in another position.

5 26. In drilling apparatus, the combination with a portable support, of a drilling tool, mechanism for rotating said drilling tool, a fluid-pressure motor for feeding and withdrawing said drilling tool, means for controlling said motor to operate 10 by fluid-pressure during feeding of said drilling tool and by suction during the withdrawal thereof, and by-pass relief valve mechanism for limiting the fluid-pressure in said motor.

15 27. In drilling apparatus, the combination with a portable support, of a drilling tool, mechanism comprising a fluid-pressure motor for feeding said drilling tool by pressure and withdrawing the same by suction, means comprising a valve for controlling said motor, and relief valve mechanism for automatically limiting the pressure in 20 in said motor.

25 28. In drilling apparatus, the combination with a portable support, of a drilling tool, means comprising a fluid-pressure motor for operating said drilling tool, means comprising an additional fluid-pressure motor for adjusting the position of said tool, said last-named motor comprising a cylinder and a piston and a piston rod connected to said piston and extending from one end of 30 said cylinder, a valve connected to said cylinder to control the flow to and from opposite sides of said piston, a valve for controlling said first-named motor, connections between a source of fluid-pressure and said motor through said valves, 35 a suction line, and a valve in the suction line to compensate for the displacement of said piston rod.

40 29. In drilling apparatus, the combination with a portable support, of a drilling tool mounted thereon, means for operating said drilling tool, means comprising a double-acting hydraulic motor for adjusting the position of said drilling tool, said motor comprising a cylinder with a piston reciprocable therein and a piston rod extending 45 from one end of said cylinder, a pump, supply pipes connected to both ends of said cylinder, a valve for controlling said motor, a supply tank for liquid, branching suction pipes leading to said tank and the suction side of said pump, a 50 valve in the branch leading to said tank, and a pipe adapted to connect that end of said cylinder through which said piston rod extends to both branch pipes to enable said pump to draw from the tank as well as the cylinder when said piston 55 rod is being moved out from said cylinder and said last-named valve is open.

60 30. In drilling apparatus, the combination with a support, of a drilling tool mounted thereon, means for operating said drilling tool comprising a hydraulic motor, means comprising another hydraulic motor for adjusting the position of said drilling tool, said last-named motor comprising a cylinder and a piston and a piston rod extending from one end of said cylinder, two valves 65 one for controlling each motor, a hydraulic pump, means for connecting said pump through said valves to said motors so that only one motor can be operated at a time, a supply tank for liquid, branching suction pipes leading to said tank and 70 to the suction side of said pump, a valve in the branch leading to the tank, and a pipe connected between said branching pipes and the valve for controlling the first-named motor, said first-named valves being operable to effect operation 75 of said first-named motor when the valve in the

tank suction branch is closed and to effect operation of said adjusting motor when the valve in said tank suction branch is open.

31. A self-contained drilling unit comprising an elongated support, a drill mounted on the outer end thereof, a hydraulic motor for feeding said drill, a pump on the rear end of said support, means extending from the rear portion of said support to the forward end thereof to rotate said drill, and a motor on said support between said 10 pump and said rotating mechanism and operatively connected to both. 5

32. A self-contained drilling unit comprising an elongated boom, a supplemental support pivotally mounted at the outer end of said boom, a 15 rotary drill mounted on said supplemental support, a fluid-pressure pump mounted on said support to move bodily therewith and operatively connected to said drill to feed the same axially, means extending from the rear end portion of 20 said boom to the forward end thereof to rotate said drill in its adjusted position, a pump mounted on said boom, and a motor connected to said rotating means and said pump to drive the same. 25

33. A self-contained drilling unit comprising a main support, an elongated boom rotatably mounted on said support, a pump on said support, a supplemental support pivotally mounted at the outer end of said boom on an axis at right angles to the axis of said boom, a rotary 30 drill mounted on said supplemental support, a fluid-pressure motor on said supplemental support adapted to be connected to said pump and connected to said drill to feed the same axially in adjusted position, means extending from said 35 main support along said boom to said supplemental support for rotating said drill, a motor on said main support connected to said pump and said rotating means to drive the same, and means for rotating said boom and drill relatively to said 40 main support. 45

34. Drilling apparatus comprising a fluid-pressure motor having a piston and a cylinder, a spring-pressed device comprising a cup and a spring to cushion the stopping of said piston and to start the piston on its return stroke when the pressure on the piston is sufficiently relieved, means comprising an annular flange on said cup 50 slidable along an annular space to limit the compression and expansion of said spring, and means for controlling the operation of said fluid-pressure motor. 55

35. Drilling apparatus comprising a fluid-pressure motor having a piston, a rotary and sliding feed shaft, a ball bearing connection between said 60 feed shaft and said piston to enable the latter to travel rectilinearly while said shaft slides and rotates, a cylindrical cup-shaped extension on said piston, a bearing block fitting closely on said shaft adjacent to said ball bearing, and a cylindrical screw-threaded connection between said cup-shaped cylindrical extension and the periphery of 65 said bearing block to enable relative turning thereof on the axis of said shaft to afford a complete closure for said ball bearing. 70

36. Drilling apparatus comprising a fluid-pressure motor having a cup-shaped piston, a rotary and sliding feed shaft, a ball bearing at one end of said shaft in said cup-shaped piston, said cup-shaped piston being imperforate, and a bearing block having threads therein to provide a connection with said piston to coat with the latter to seal said ball bearing in the enclosure formed by said cup-shaped piston and the threaded connection between the latter and said bearing block. 75

37. Drilling apparatus comprising a fluid-pressure motor having an imperforate piston, a rotary and sliding feed shaft, a ball bearing connection between said shaft and said piston, a bearing block, and a rotary screw-threaded connection between said imperforate piston and said block formed by co-operating threads on each to form a liquid-tight enclosure for said ball bearing.

38. Drilling apparatus comprising a fluid-pressure motor having a cup-shaped imperforate piston, a rotary feed shaft, a thrust ball bearing between said shaft and said imperforate piston, a bearing block, and a rotary screw-threaded connection between said imperforate piston and said bearing block formed by co-operating threads on each to confine said ball bearing to a hermetically sealed chamber.

39. In drilling apparatus, the combination with supporting framework, of a drilling tool mounted thereon, means for rotating said drilling tool, a fluid-pressure motor for feeding said drilling tool, another fluid-pressure motor for adjusting the position of said drilling tool, two controlling valves one for each of said fluid-pressure motors, and conduits connecting a source of fluid pressure to said fluid-pressure motors through controlling valves connected in series thereby rendering said valves interdependent by compelling the fluid-pressure medium to flow through both the valves in series whenever either fluid-pressure motor is operated and thus enabling either fluid-pressure motor to be operated while the other is cut off from the source of fluid pressure.

40. In drilling apparatus, the combination with a portable support, of a horizontal turntable mounted on said support for rotation relatively thereto about a vertical axis, means for locking said turntable in its different positions of adjustment relative to said support, an elongated boom pivotally mounted on said turntable to swing relatively thereto on a horizontal axis, a drilling tool adjustably mounted on the outer extremity of said boom, a motor and a fluid-pressure pump driven thereby, both mounted on the rear end of said boom to swing bodily therewith, a fluid-pressure motor connected to the rear end of said drilling tool in alignment therewith, mechanism extending along said boom and driven by the said first named motor for rotating said drilling tool, means for controlling connection of said pump to said fluid-pressure motor to effect axial feed of said drilling tool while being rotated, and motor operated mechanism for swinging said boom on its horizontal axis relatively to said turntable irrespective of the position of the latter relative to said support.

41. In drilling apparatus, the combination with supporting framework, of a drilling tool mounted thereon, motor operated means for rotating said drilling tool, a fluid-pressure motor for feeding said drilling tool and retracting the same in the opposite direction, a fluid-pressure pump, an additional fluid-pressure motor for adjusting the position of said drilling tool relative to said supporting framework, two valves one for controlling one of said fluid-pressure motors, and the other for controlling the other fluid-pressure motor, and conduits connecting said valves in series to enable the adjusting motor to be cut off and locked during the operation of the drill including rotation and feed thereof.

42. In drilling apparatus, the combination with a portable supporting frame, of a drill support pivotally mounted on said frame to swing relatively thereto on a horizontal transverse axis, a

drilling tool mounted on said drill support, a motor mounted on said drill support, power-transmission means between said motor and said drilling tool for rotating the latter, a pump mounted on said drill support and operatively connected to said motor, a fluid-pressure motor connected to said drilling tool to feed the same, a fluid-pressure motor pivotally connected at one end to said frame and at its other end pivotally connected to said drill support, and means for controlling the fluid-pressure from said pump to said fluid-pressure motors.

43. In drilling apparatus, the combination with a supporting frame, of a drill support pivotally connected to said frame on a transverse horizontal axis extending across the top of said drill support, a motor mounted on said drill support at the rear end portion thereof, a pump mounted on said drill support at the rear end thereof, a drilling tool mounted on the outer end of said drill support, mechanism connected to said motor for driving said pump, mechanism connected between said motor and said drilling tool for rotating the latter, a fluid-pressure motor for feeding the drilling tool during rotation thereof, and means for controlling the fluid pressure from said pump to said fluid pressure motor.

44. A drilling unit comprising an elongated boom, tubular means for supporting said boom for rotation on its longitudinal axis, a motor having a frame rigidly connected to said tubular means, mechanism for rotating said boom relatively to said tubular supporting means, a drilling tool mounted on the outer end of said boom, means operated by said motor and extending through said tubular supporting means for driving said drilling tool, a pump carried by the rear end of said motor, and connected to the latter for operation thereby, a fluid pressure motor for feeding said drilling tool, and means for controlling fluid pressure from said pump to said fluid pressure motor.

45. A drilling unit comprising a motor having a frame and a driving shaft extending from opposite ends thereof, a tubular support secured to the front end of said motor frame, a pump and operating mechanism therefor connected to the rear end of said motor shaft and mounted at the rear end of the motor frame, an elongated boom having its rear end rotatably mounted in said tubular support, worm gearing at the outer end of said tubular support for rotating said boom relatively to said support, a drilling tool at the outer end of said boom, means connected between the front end of the motor shaft and said drilling tool and extending through said boom for rotating said drilling tool, a fluid-pressure motor connected to said drilling tool to feed the same during rotation, and means for controlling fluid pressure from said pump to said fluid-pressure motor.

46. A drilling unit comprising a motor having a frame, a supporting tube rigidly connected to said frame, an elongated boom rotatably supported by said supporting tube, means between said tube and said boom for rotating the latter, a drilling tool mounted on said boom, mechanism between said motor and said drilling tool for rotating the latter, means for feeding said drilling tool, and means for pivotally supporting the drilling unit by suspending said motor frame on an axis extending transversely of the upper side thereof.

47. A drilling unit comprising an elongated boom, a pump mounted thereon, a drilling tool

- 5 pivoted to the outer end of said boom for adjustment relative thereto on an axis extending at right angles to the axis of said boom, a fluid-pressure motor in alignment with said boom, a fluid-pressure motor in alignment with said boom, a fluid-pressure 10
5 tool and offset laterally from said boom, means mounted on said boom for driving said drilling tool irrespective of its adjusted position relative to said boom, and means for controlling the fluid-pressure from said pump to said fluid-pressure
10 motor to operate the latter in any adjusted position of the drilling tool.
- 15 48. A drilling unit comprising an elongated boom having a longitudinal passageway therethrough closed from the atmosphere, a drilling tool at the outer end of said boom, a motor, a gear casing connecting said motor to said boom, said gear casing being in communication with said passageway and having a vent to the atmosphere, a fluid-pressure motor connected to said drilling
20 tool, mechanism for connecting the space at one end of said fluid-pressure motor with said passageway, said fluid-pressure motor comprising a piston one side of which effects movement of air along said passageway and through said vent
25 when said piston is moved in opposite directions.
- 25 49. In drilling apparatus, the combination with a frame, of a drill support pivotally attached to said frame, a drill mechanism carried by said drill support, an electric motor carried by said
30 drill support, a hydraulic pump driven by said motor, a hydraulic motor for pivoting said drill support with respect to said frame, a second hydraulic motor for feeding said drill mechanism, means interconnecting said motor and said drill
35 mechanism to rotate the latter from the former,

and means for controlling said hydraulic motors from said pump.

50. In drilling apparatus, the combination with a frame, of a drill support pivotally attached to said frame, a drill mechanism carried by said drill support, an electric motor, a hydraulic pump driven by said motor, a hydraulic motor for pivoting said drill support with respect to said frame, a second hydraulic motor for feeding said drill mechanism, means interconnecting said motor and said drill mechanism to rotate the latter from the former, and means for controlling said hydraulic motors from said pump. 10

51. In drilling apparatus, the combination with a frame, of a drill support pivotally attached to said frame, a drill mechanism carried by said drill support, an electric motor carried by said drill support, a hydraulic pump driven by said motor, a hydraulic motor for pivoting said drill support with respect to said frame, means interconnecting said motor and said drill mechanism to rotate the latter from the former, and means for controlling said hydraulic motor from said pump. 15

52. In drilling apparatus, the combination with a frame, of a drill support pivotally attached to said frame, a drill mechanism carried by said drill support, an electric motor, a hydraulic pump driven by said motor, a hydraulic motor for pivoting said drill support with respect to said frame, means interconnecting said motor and said drill mechanism to rotate the latter from the former, and means for controlling said hydraulic motor from said pump. 20

EDWARD G. LEWIS. 35
